(57) CLAIM

The ornamental design for a rope clip, as shown and described.

DESCRIPTION

FIG. 1 is a perspective view of a rope clip of the present design;

FIG. 2 is a top view of FIG. 1;

FIG. 3 is a side view of FIG. 1;

FIG. 4 is a left frontal view of FIGS. 1, 2 and 3;

FIG. 5 is a right frontal view of FIGS. 1, 2 and 3; and,

FIG. 6 is a reduced scale, environmental view of the present rope clip in use.

The broken lines showing a rope are for the purposes of illustrating environment and form no part of the claimed design.
